(57) **CLAIM**

The ornamental design for a multifunctional fitness board, as shown and described.

DESCRIPTION

FIG. 1 is a front, left, and bottom perspective view of a first embodiment of a multifunctional fitness board showing my new design;

FIG. 2 is a rear, right, and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded front, left, and bottom perspective view thereof, where the multifunctional fitness board is in an alternate configuration of use;

FIG. 10 is a front, left, and bottom perspective view of a second embodiment of a multifunctional fitness board showing my new design;

FIG. 11 is a rear, right, and top perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is an exploded front, left, and bottom perspective view thereof, where the multifunctional fitness board is in an alternate configuration of use.

The broken lines in the drawings depict portions of the multifunctional fitness board that form no part of the claimed design.

1 Claim, 18 Drawing Sheets
